UNITED STATES PATENT OFFICE.

FRANK J. SCHLEICHER, OF ST. LOUIS, MISSOURI.

DESIGN FOR A BOX.

Application filed June 27, 1928. Serial No. 27,295. Term of patent 14 years.

To all whom it may concern:

Be it known that I, FRANK J. SCHLEICHER, a citizen of the United States, residing at the city of St. Louis and State of Missouri, have invented a new, original, and ornamental Design for Boxes, of which the following is a specification, reference being had to the accompanying drawing, forming part thereof.

The figure is a perspective view of a box showing my new design.

The walls of the box have along their lower marginal portions a strip 1 of a color dis-

tinctive and different from the color of the ornamental walls 2. The upper edge of the strip 1 forms a ledge 3 around the box walls.

The lid of the box has side walls 4 enclosing the upper end of the box and of a color distinctive and different from the color of the ornamental walls 3 and the ornamental top 5 of the cover.

I claim:

The ornamental design for a box, as shown and described.

FRANK J. SCHLEICHER.
